UNITED STATES PATENT OFFICE.

CARL E. CHRISTOPHEL, OF PEARL RIVER, NEW YORK, ASSIGNOR TO DEXTER FOLDER COMPANY, OF PEARL RIVER, NEW YORK, A CORPORATION OF NEW YORK.

SHEET-FEEDING MACHINE.

1,382,952.

Specification of Letters Patent. Patented June 28, 1921.

Application filed April 9, 1919. Serial No. 288,753.

To all whom it may concern:

Be it known that I, CARL E. CHRISTOPHEL, a citizen of Germany, residing at Pearl River, county of Rockland, State of New York, have invented a certain new and useful Improvement in Sheet-Feeding Machines, of which the following is a specification.

This invention relates to sheet feeding machines and has for its object to provide an improved construction and arrangement of parts for adapting machines of this character to operate more rapidly and with greater certainty on sheets which are to be fed one by one from a pile. One of the objects of my invention is to provide an improved sheet feeding mechanism which will be effective on sheets of various kinds including sheets of thin or flimsy paper which ordinarily are difficult to separate from a pile one at a time and which are easily mutilated or mussed. The present invention contemplates in its preferred embodiment, a suitably formed lever movable about an axis into and out of position to lift a portion of a pile of sheets, a combing wheel co-operating therewith to impart graded movements to sheets composing the periodically lifted portion of said pile during the lifting movement, and a sheet gripping sucker movable into and out of position to grip the top sheet. My invention furthermore contemplates the co-operation of the lifting lever with the sucker alone or the co-operation of the lifting lever with the combing wheel alone, for effecting a preliminary separating action which may be employed in connection with any suitable mechanism for feeding off the sheets. Another object of the invention is contemplated in the construction by means of which the sheet gripping sucker can be so arranged as to be moved into and out of position to operate upon the top sheet of that portion of a pile which has been elevated by the lift lever. The utility of these devices employed one with another or all three together depends on the character of the sheets which are being operated upon.

50 In the drawings:

Figure 1 is a side elevation of a preferred embodiment of my invention taken in the direction indicated by the lower arrow on Fig. 6;

55 Fig. 2 is a similar side elevation from the

opposite side as indicated by the upper arrow in Fig. 6;

Fig. 3 is a side elevation similar to Fig. 1 showing the parts in changed positions;

Fig. 4 is a similar side elevation showing 60 a more advanced stage of the operation;

Fig. 5 is a similar side elevation showing the final phase of the operation;

Fig. 6 is a top plan view of the mechanism.

In the embodiment of my invention shown 65 on the drawings, a guide shaft 1, provided with a rack 2 serves to carry a bracket 3 which is adapted to be moved along the shaft 1 by means of a pinion (not shown) on the end of a spindle 4 provided with a hand grip 5, said pinion being rotated thereby in mesh with the rack 2. In Fig. 6 is shown the main frame 6 of a sheet separating device. Extending upwardly from said frame 6 is a guide rod 7 which slides in the spaced lugs 70 8 on the bracket 3. The screw rod 9 also projects upwardly from the frame 6 and likewise extends through the lugs 8 on the bracket 3. Threaded on the upper end of the screw rod 9 is a handle 10 which is 75 adapted to raise and lower the sheet separating device in its entirety. Journaled in the main frame 6 is a cam shaft 11 to one end of which is secured the combing wheel 12. The other end of said shaft carries a 80 bevel gear 13 which meshes with a similar gear 14 mounted on a power shaft 15. Said drive and cam shaft 11 is thus rotated in the direction of the arrows shown on Fig. 6. It will be seen therefore that the combing 85 instrumental 12 rotates on a fixed axis. The frame 6 is provided with rearwardly presented arms 16 which carry a shaft or bolt 17. Pivotedly mounted on the shaft or bolt 17 is a lifting lever 18 which roughly conforms in contour to the periphery of the comb 12 when said lever is in operative position with respect to said comb. For this purpose, the lower end of said lever is pointed at 19 to adapt it to be driven into 90 a pile of sheets on a table 20 for momentarily lifting a portion of said pile. Rigidly secured to the shaft or bolt 17 are spaced forwardly presented bracket arms 21 between 95 which extends a spring rod 22. Pins or trunnions 23 which are journaled between the arms 21, carry a guide or enlargement 24 in which the rod 22 is slidably mounted. Surrounding the rod 22 and interposed between the guide or enlargement 24 and a 100 110

thumb nut 25 on the upper end of rod 22, is a spring 26. At its lower end, the rod 22 is connected at 27 to the lift lever 18. It will be seen therefore that the spring 26 tends 5 to throw the lift lever 18 into operating engagement with the pile of sheets. The lift lever 18 carries a pin or stud 28 on which is pivotally mounted one end of a cam lever 29. The other end of said cam lever comprises laterally spaced arms 30 which slidably engage the cam shaft 11. Journalized on the cam lever 29 is a roller 31 which travels on a cam 32 keyed to the cam shaft 11. At 10 each inward movement of lift lever 18, a portion of the pile is lifted in the manner indicated in Fig. 3 just in time for said portion of the pile to be operated upon by comber 12. Depending from the stud or bolt 17 is a bracket arm 33 at the lower end 15 of which is mounted a pin 34 which serves to pivot a curved arm 35 which is provided on its outer end with a plurality of holes or sockets 36 for the reception of a stud 37 which carries a suction tube 38 provided at 20 its lower end with a sheet gripping sucker 39. Suitable means for moving this sucker into and out of position to grip the top sheet of the pile, is provided by a cam 40 over which travels a roller 41 which is journalized 25 on a pin 42 carried by the lever arm 35. On the lower end of a depending bracket arm 43 is a laterally projecting guide pin 44 on which slides a clamping foot 45 which is provided with a suitable cam surface 46 and an upwardly extending slot 47 which adapts 30 said clamping foot to move downwardly and upwardly prior to and after each inward and outward movement. The clamp foot 45 is swingingly suspended from a pin 48 carried by a cam lever 49 which pivots on the 35 shaft or bolt 17. Said cam lever 49 is provided with a rearwardly projecting arm 50 between which and a similar arm 51 of the clamping foot 45 extends a spring 52 which 40 tends to draw them together. This spring is thereby adapted to perform a double function, namely, to impart the movements to said clamping foot 45 while at the same time serving to hold a cam roller 53 which is 45 journalized on the cam lever 39, against the cam 54 which serves to govern the movements of these parts. The usual wind pipe 55 is connected to a nozzle 56 which is suitably presented to provide a blanket of air 55 under the upper sheet after it has been raised by the sucker 39. The operation of the mechanism will now be readily understood and briefly described as follows:

According to the relative positions of the 60 parts shown in Figs. 1, 2 and 6, the sucker 39 has a short time before released the preceding top sheet which is being withdrawn from the pile by suitable means not shown on the drawings. The cam roller 41 (which 65 controls the rise and fall of the sucker 39) is soon to be permitted to move to the inner run of cam 40 to permit the sucker 39 to assume its lowest position in which the next succeeding top sheet will be drawn into engagement therewith. On the other hand 70 the clamping foot 45 is about to be shifted toward the right and lifted by means of the cam 54 which moves the cam roller 53 into its extreme right hand position according to Fig. 1. At the same time, the lifting lever 75 18 is about to be thrown into the position shown in Fig. 3 by reason of cam roller 31 being released by cam 32 to assume its extreme left hand position. As shown in Fig. 3, clamping foot 45 has been lifted by cam 80 roller 53 being forced to the outer run of cam 54, while the lifting lever 18 has displaced upwardly a portion of the pile (in the present instance one corner) into position to have the comber 12 operate on the 85 top sheets. According to Fig. 3, the sucker is moving downward as the comber 12 begins its action upon the top sheets. By the time sucker 39 has reached its lowest position as shown in Fig. 4, the top of the pile has 90 been drawn into a suitable position to be attached thereto by suction. Immediately afterward, the cam roller 31 is forced to the outer run of cam 32 to throw the lift lever 18 away from the pile as shown in Fig. 5. 95 At the same time, the clamping foot 45 has moved forward and downward, brushing past the edge of the top sheet during the sucker's rising movement which is occasioned by cam roller 41 being forced to the 100 outer run of cam 40. The parts are next moved into the relative positions shown in Figs. 1, 2 and 6, the separated top sheet being released by the sucker and passed forwardly from the machine. The successive 105 operations are thus produced in the sequence pointed out above.

I claim:

1. In a sheet feeding machine, a sheet gripping instrumentality, means for supporting a pile of sheets and holding one portion of said pile displaced relatively to other portions of said pile, and means operating upon the top sheet of said pile in a direction away from said sheet gripping instrumentality for moving said top sheet into position to be engaged by said sheet gripping instrumentality. 110
2. In a sheet feeding machine, a sheet gripping instrumentality, means for supporting a pile of sheets and holding one portion of said pile displaced relatively to other portions of said pile, and means operating upon the displaced portion of the top sheet of said pile in a direction away from said sheet gripping instrumentality and moving said top sheet into position to be engaged by said sheet gripping instrumentality. 120
3. In a sheet feeding machine, a sheet gripping instrumentality, means for sup- 125

- porting a pile of sheets, means for displacing one portion of said pile relatively to another, and means operating upon the top sheet of said pile in a direction away from 5 said sheet gripping instrumentality and intermediately of said sheet gripping instrumentality and said displacing means for moving said top sheet into position to be engaged by said sheet gripping instrumentality. 10
4. In a sheet feeding machine, a pile supporting table, means for imparting a bend to a portion of said pile, a sheet gripping instrumentality, means for straightening the 15 top sheet of said pile across said bend for moving it into a position to be gripped by said instrumentality, and means for introducing a blanket of air beneath said top sheet. 15
5. In a sheet feeding machine, a pile holding table, means for lifting a portion of said pile, a sheet gripping instrumentality arranged above a pile of sheets on said table, and means operating on the top sheet of 20 said pile in a direction away from said sheet gripping instrumentality for straightening said top sheet and moving it nearer said sheet gripping instrumentality. 25
6. In a sheet feeding machine, the combination with a pile holding table, of a sucker and means for lifting a portion of a pile of sheets from said table and toward said sucker, and a sheet combing instrumentality operating on the lifted portion of said pile 30 for drawing out the top sheet into position to be engaged by said sucker. 35
7. In a sheet feeding machine, the combination with a table for supporting a pile of sheets, of a sucker movable into and out of 40 operating position, a lever movable into and out of position to lift a portion of a pile of sheets into a position from which the sucker engages the top sheet for separating it from the pile, and means for periodically moving 45 said sucker and lifting lever into and out of coöperating positions. 50
8. In a sheet feeding machine, a pile holding table, means for lifting a portion of said pile, a sheet gripping instrumentality arranged above a pile of sheets on said table, and sheet combing means operating on the 55 top sheet of said pile in a direction away from the said sheet gripping instrumentality for straightening said top sheet and moving it nearer said sheet gripping instrumentality. 60
9. In a sheet feeding machine, a pile holding table, means for lifting a portion of said pile, a sheet gripping instrumentality arranged above a pile of sheets on said table, and sheet combing means operating on the top sheet of said pile in a direction away from the said sheet gripping instrumentality for straightening said top sheet and moving it nearer said sheet gripping instrumentality. 65
- ity, said lifting means including a lever movable about an axis into and out of position to hold said lifted portion of the pile in momentary engagement with said sheet combing means. 70
10. In a sheet feeding machine, the combination with a table for holding a pile of sheets, of sheet separating mechanism including a sucker, a combing wheel journaled on an axis above said table and having its operating periphery normally spaced from a pile of sheets on said table, and a lifting lever movable into and out of position to raise a portion of said pile into operating engagement with said combing wheel. 75
11. In a sheet feeding machine, the combination with a table for holding a pile of sheets, of sheet separating mechanism including a sucker, a combing wheel journaled on an axis above said table and having its operating periphery normally spaced from a pile of sheets on said table, and a lifting lever movable into and out of position to raise a portion of said pile into operating engagement with said combing wheel, said lifting lever being shaped to conform approximately to the periphery of said combing wheel. 80
12. In a sheet feeding machine, a pile supporting table, a lifting lever suitably mounted for lifting a corner of a pile of sheets on said table, a sheet gripping sucker movable toward and away from said pile of sheets and a combing wheel arranged above said pile of sheets and between said sucker and said lifting lever. 85
13. In a sheet feeding machine, a pile holding table, a lever for lifting a portion of said pile, a sheet gripping instrumentality arranged above a pile of sheets on said table, means for moving said lever and sheet gripping instrumentality alternately toward and away from each other, and a combing wheel arranged between said lifting lever and sheet gripping instrumentality. 90
14. In a sheet feeding machine, a table for holding a pile of sheets, a combing instrumentality adapted to operate on a portion of said pile of sheets when it is raised above the upper surface of said pile, and a lifting lever movable into and out of position to lift a portion of said pile into position to be engaged by said combing instrumentality. 115
15. In a sheet feeding machine, a table for holding a pile of sheets, a pile comber rotatable on a fixed axis above said table, means for momentarily lifting a portion of a pile of sheets into and out of engagement with said pile comber for effecting a preliminary separation, and means movable into and out of gripping engagement with the lifted portion of the separated upper sheet for removing said sheet. 120
- 125
- 130

16. In a sheet feeding machine, a table for holding a pile of sheets, a rotary pile comber arranged above said table, a lever suitably formed and movable into and out of position to lift a portion of said pile into position to be engaged by said comber, and a sheet engaging sucker movable into and out of position to engage the lifted portion of the top sheet.
- 10 17. In a sheet feeding machine, a table for holding a pile of sheets, a rotary pile comber arranged above said table, a lever suitably formed and movable into and out of position to lift a portion of said pile into position to be engaged by said comber, and a sheet engaging sucker movable into and out of position to engage the lifted portion of the top sheet, said sucker and lifting lever being movable toward said rotary comber from opposite sides thereof.
- 15 18. In a sheet feeding machine, a sheet engaging instrumentality having a sphere of action spaced above the top surface of a pile of sheets, means for lifting a portion of said pile into the sphere of action of said sheet engaging instrumentality, and sheet gripping means movable into and out of position to grip a sheet which has been displaced by said sheet engaging instrumentality.
- 20 19. In a sheet feeding machine, a sheet gripper movable into and out of sheet gripping position above a pile of sheets, means for displacing portions of some of the sheets of said pile relatively to other portions of the same sheets, and means operating on the displaced portion of the top sheet for moving a portion of said top sheet into position to be engaged by said sheet gripper in sheet gripping position, said displacing means and said top sheet moving means being movable into and out of cooperating relation to each other and on opposite sides of the lifted portion of said sheets.
- 25 20. In a sheet feeding machine, a sheet gripper movable into and out of its lowermost position above a pile of sheets, means for lifting a portion of said pile adjacent to said gripper in its lowermost position, and a sheet combing device operating upon the lifted portion of the top sheet of said pile for drawing said top sheet into position to be engaged by said sheet gripper.

CARL E. CHRISTOPHEL.
